CONTROL SYSTEM.

1,365,322.

Specification of Letters Patent. Patented Jan. 11, 1921.

Application filed December 2, 1918. Serial No. 264,981.

To all whom it may concern:

Be it known that I, HENRY D. JAMES, a citizen of the United States, and a resident of Edgewood Park, in the county of Allegheny and State of Pennsylvania, have invented a new and useful Improvement in Control Systems, of which the following is a specification.

My invention relates to motor-control systems.

The object of my invention is to provide a control system with the aid of which it shall be possible to start a motor, and to accelerate it and to control its speed in accordance with predetermined conditions.

According to my invention, an accelerating resistor is short-circuited by means of contactors of the now well known "lock-out" type having the peculiar property of being maintained open when the current is above a predetermined value and of closing when the current falls to that value. I connect the actuating coils of the contactors between different-potential points of the starting resistor. As the coils become deenergized when the starting resistor is short-circuited, it is necessary to provide some means for maintaining the resistor short-circuited. In one form of my invention, I effect this result by energizing the last contactor to close by the electromotive force of the motor. According to another form of my invention, the actuating coil of the last contactor, or a plurality of the contactors may, after closing, be connected directly across the line.

My invention will be made clear in connection with the accompanying drawings in which Figures 1, 2 and 3 are diagrammatic representations of different forms of my invention.

Referring to Figs. 1 and 2, an electric motor, having an armature 1 and a shunt field-magnet winding 2, is connected between line conductors 3 and 4, separated by a line contactor 5, which is adapted to be closed by means of an actuating coil 6, the circuit of which may be closed by a master switch 7. An accelerating resistor, portions of which are indicated at 8, 9 and 10, is connected in series with the armature 1 and is adapted to be short-circuited by a plurality of contactors 11, 12 and 13, having actuating coils 14, 15 and 16.

The contactors 11 and 12 of Fig. 1 are of

the "lockout" type; that is, when the current flowing through their actuating coils is above a predetermined value, they will be maintained in the illustrated, open positions; and when the current falls to this value, they will close. The contactor 13 of the system of Fig. 2 is, like the contactors 11 and 12, a "lockout" contactor, but the circuit of its coil 16 is connected in series with a resistor 17 of high resistance, across the line conductors 3 and 4.

In Fig. 1, the actuating coils 14 and 15 of the contactors 11 and 12 are connected at 18 and 19, in parallel, across the accelerating resistor. The contactor 11 of Fig. 2 is connected, at 19 and 20, between one end of the resistor and the point connecting the portions 8 and 9 of the resistor, and the contactor 15 is connected at 18 and 19, across the whole resistor. The contactor 13 of Fig. 2 is adapted to bridge contact members 21, 75 when occupying its open position, for the purpose of then closing a circuit for its actuating coil 16, which extends from the point 18, through the contact members 21 and the coil 16, to the point 19.

The operation of the system shown in Fig. 1 may be described as follows. Assuming that the master switch 7 has been closed to cause the energization of the coil 6, and thereby to cause the closing of the contactor 5, current will flow from the line conductor 3, through the armature 1 and the accelerating resistor 8, 9, 10, and the shunt field-magnet winding 2, in parallel, to the point 19 and thence, through the line contactor 5, 90 to the line conductor 4. A shunt circuit is, at the same time, established for the coils 14 and 15 of the contactors 11 and 12, between the points 18 and 19. If the motor is starting under a heavy load, the current 95 will be of high value and will serve to maintain the contactors 11 and 12 open. When the current falls to a predetermined value, the contactor 11,—assuming that the contactors are properly adjusted,—will 100 close first to short-circuit the portion 10 of the accelerating resistor. This will cause an immediate rise in the current value which will serve to maintain the contactor 12 open for a predetermined period of time until 105 the current again falls, this time to the closing value of the contactor 12. The closing of this contactor results in short-cir-

cuiting the additional portion 9 of the accelerating resistor. Ultimately, when the counter-electromotive force of the motor rises to a sufficiently large value, the contactor 13 will be closed to short-circuit the remaining portion 8 of the accelerating resistor, thereby resulting in connecting the motor directly across the line. The short-circuiting of the entire resistor results, also, in de- 10 energizing the coils 14 and 15 of the contactors 11 and 12, since they are controlled by the potential difference of the points 18 and 19. This has no result upon the operation of the motor, however, because of the 15 contactor 13, which will remain closed so long as the counter-electromotive force of the motor is above a predetermined value.

If the motor be started under a moderately heavy load, the current will fall so 20 rapidly from a high value to a value below that at which the contactor 11 is adapted to be closed that this contactor will remain open. The contactors 12 and 13, however, will close in order, as above described. 25 Similarly, if the motor be started under a light load, the starting current may drop from a high value to a value below that at which the contactor 12 is designed to close, with the result that the contactors 11 and 30 12 will remain open and the accelerating resistor will be controlled entirely by the counter-electromotive-force contactor 13.

I thus provide a system having the requisite kinds of speed control adapted to the 35 load on the motor.

The operation of the system of Fig. 2 is somewhat different, for the time of closing of the contactor 11 is controlled, not merely by well known adjustments of the 40 contactor itself, but also by the fact that its coil 14 is connected across a portion only of the accelerating resistor. The contactor 11 will, accordingly, close, before the contactor 12, to short-circuit the resistor portion 10. 45 Upon the closing of this contactor 11, the coil 15 will be controlled by the potential difference between the point 18 and the point 22, which latter point separates the resistor portions 9 and 10, the resistor por- 50 tions having been short-circuited by the closing of the contactor 11. The contactor 12 will then close at the proper time, in accordance with current conditions, as de- 55 scribed in connection with the description of Fig. 1, to short-circuit the resistor portion 9. The coil 16 will now be controlled by the difference of potential between the points 18 and 20 and, when the contactor 13 finally closes to short-circuit the resistor portion 60 8, the circuit of the actuating coil 16 will be broken at the contact members 21 but the coil will continue to be energized by the circuit extending from the line conductor 3 through the resistor 17 and the coil 65 16, to the point 19 and thence, through the

contactor 5, to the line conductor 4. This circuit, though not sufficiently energized to cause the actuation of the contactor 13 in the first instance, will maintain the contactor in closed position. 70

It will be obvious that the contactors 11, 12 and 13 of the system of Fig. 2 may be connected in parallel, as is the case with the contactors 11 and 12 of Fig. 1, and that the latter contactors may be connected to 75 different intermediate points of the accelerating resistor, as in Fig. 2.

It will be obvious, too, that the contactor 13 of Fig. 1 may be replaced by a contactor like that numbered 13 in Fig. 2. The circuit of each of the coils 14, 15 and 16, in that event, since they will be all connected in parallel, and including contact members like those numbered 21 in Fig. 2, will be closed when the contactor 13 occupies its 85 open position. This is diagrammatically represented in Fig. 3 in a system employing but two contactors. Other modifications, too, will occur to those skilled in the art, and I desire, therefore that the appended claims shall be construed broadly except in so far as limitations may be expressly imposed therein. 90

I claim as my invention:

1. The combination with an electric motor 95 and a resistor in circuit therewith, of a plurality of switches for controlling said resistor, one of said switches having lock-out characteristics and another of said switches being so connected as to close in accordance with the value of the current traversing said motor and to be thereafter responsive to the value of the counter-electromotive force of said motor. 100

2. The combination with an electric motor, of means for controlling the same comprising a starting resistor, a plurality of electromagnetic switches for controlling the resistor which hold open when the energizing current is relatively high and close when the 110 current decreases to a lower value, and connections whereby the energizing winding of one switch is connected between points of different potential of said resistor to cause it to close when the current through the resistor decreases and the winding of another switch is thereupon effective to control said other switch. 115

3. The combination with an electric motor, of means for controlling the same comprising a starting resistor, a plurality of electromagnetic switches for controlling the resistor which hold open when the energizing current is relatively high and close when the current decreases to a lower value, each having an energizing coil adjusted and connected between points of different potential of said resistor to cause them to successively close as the current through the 120 resistor decreases. 125

4. The combination with an electric motor having a resistor associated therewith, of a pair of electromagnetic switches for controlling said resistor which hold open when the 5 energizing current is relatively high and close when the current decreases to a lower value, one of said switches having an actuating coil connected between points of different potential of said resistor, and the 10 other of said switches having a coil that is energized to maintain said other switch closed during the normal operation of said motor.
5. The combination with an electric motor 15 having a resistor associated therewith, and a source of energy for said motor, of an electromagnetic switch for controlling said resistor which holds open when the energizing current is relatively high and closes 20 when the current decreases to a lower value and having an actuating coil connected between points of different potential of said resistor, and means for energizing said coil by energy from said source to maintain said 25 switch closed upon the closing of said switch.
6. The combination with an electric motor
- having a resistor associated therewith, of a plurality of electromagnetic switches for controlling said resistor which hold open 30 when the energizing current is relatively high and close when the current decreases to a lower value, each having an actuating coil connected across different portions of said resistor, and connections whereby, upon 35 the closing of one of said switches, a portion of said resistor, across which the coil of another of said switches is connected, is short-circuited.
7. The combination with an electric motor 40 having a resistor associated therewith, of a switch for controlling said resistor which holds open when the energizing current is relatively high and closes when the current decreases to a lower value, and having an 45 actuating coil connected between points of different potential of said resistor and another switch for controlling said resistor having an actuating coil responsive to the counter-electromotive force of said motor. 50

In testimony whereof, I have hereunto subscribed my name this 27th day of Nov., 1918.

HENRY D. JAMES.
